[57] CLAIM

The ornamental design for a storage cabinet, as shown and described.

DESCRIPTION

FIG. 1 is a perspective view of a storage cabinet showing my new design;

FIG. 2 is a front elevational view thereof;

FIG. 3 is the left side elevational view, the right side being a mirror image thereof;

FIG. 4 is a rear elevational view thereof;

FIG. 5 is a plan view thereof;

FIG. 6 is a bottom plan view thereof;

FIG. 7 is a perspective view of a second embodiment of a storage cabinet shown in FIG. 1, the top plan view being substantially similar to FIG. 5, and the rear elevational view being substantially similar to FIG. 4;

FIG. 8 is a front elevational view thereof;

FIG. 9 is the left side elevational view, the right side being a mirror image thereof;

FIG. 10 is a bottom plan view thereof;

FIG. 11 is a perspective view of a third embodiment of a storage cabinet shown in FIG. 1, the left side elevational view being identical with FIG. 9, the right side elevational view being a mirror image of FIG. 9, the top plan view being substantially similar to FIG. 5 and the rear elevational view being substantially similar to FIG. 4;

FIG. 12 is the front elevational view thereof; and,

FIG. 13 is a bottom plan view thereof.

FIG. 1

FIG. 2

FIG. 3

FIG. 4

FIG. 5

FIG. 6

FIG. 9

FIG. 7

FIG. 11

FIG. 8

FIG. 10

FIG. 12

FIG. 13
